UNITED STATES PATENT OFFICE.

RIICHI WATANABE, OF TOKYO, JAPAN.

RESPIRATOR.

1,331,601.

Specification of Letters Patent. Patented Feb. 24, 1920.

Application filed May 8, 1918. Serial No. 233,262.

To all whom it may concern:

Be it known that I, RIICHI WATANABE, a subject of the Emperor of Japan, and a resident of No. 11 Nakano-Cho, Azabu-Ku, 5 city of Tokyo, Empire of Japan, merchant, have invented new and useful Improvements in Respirators, of which the following is a specification.

This invention relates to improvements in 10 respirators for use in deep water, or in the upper air, by divers, aviators, and the like, and comprises a casing forming an air chamber adapted to fit over and cover the face of the user between the eye brows and the 15 upper lip so that the user may be able to inhale the air admitted into the said air chamber through his nose and to exhale from the mouth.

Another object is to provide a respirator 20 which is efficient and safe without giving any difficulty to the diver when working at a considerable depth of water, or to the aviator operating at a height where the air is considerably rarefied.

25 Another object is to provide a respirator which is efficient for preventing the waste of oxygen when the same is used as an inhaler in the administration of oxygen as in a certain class of medical treatment; and 30 finally to provide a respirator which will serve as a safe guard against poisonous gases, smokes, and the like.

In the drawings, Figure 1 is a perspective view of my improved respirator having an 35 air admitting valve mounted by a supporting lever which governs the position of the valve and which also serves as an inlet pipe of air into the air chamber.

Fig. 2 is a plan view or modification of 40 the air valve.

Fig. 3 is a perspective view of the invention showing a further modification of the air valve.

Fig. 4 is a side elevation as applied to the 45 diver carrying on his back and waist the main and secondary air reservoir respectively.

Fig. 5 is a detail cross sectional view, 50 through the mask, valve and valve casing, and showing the levers which control said valve.

Referring to the drawing, the numeral 1 55 designates an inclosed casing made of rubber or other elastic material and which is preferably elliptical in cross section and has a front transparent closed door 2 and

curved rear peripheral edge *c* adapted to fit over the face of the user to cover the space between the eyebrows and the upper lip of the mouth. 4 is a strengthening metal externally fitted over the outer surface of the rubber casing 1 so that the same may be kept rigid and without distortion when placed in position upon the face. When thus arranged a securely sealed air chamber 60 65 is formed therein.

Upon the opposite sides of the said strengthening metal 4 and at four different points, as at 6, are suitable rings to which the ends of elastic bands 7, which are preferably of rubber pipe, are attached, the central portions of such bands being provided with suitable fastening members here shown as a hook 8 and eye 8^a, adapted to engage each other at the back of the head and thus 70 cause said elastic band to hold the air chamber casing tightly and firmly on the face to cover the eye-brows and nose, and to expose the mouth as shown in Fig. 4.

The air is supplied to the chamber 5 by 80 means of a hose 10 and a tubular valve casing 11, the said hose 10 leading from an appropriate source, preferably a bag or reservoir 21 carried upon the man's back in the manner shown in Fig. 4. 85

The air inlet valve may be of any suitable form. As shown in Fig. 1, the valve member 9 has a depending rod 13 which is provided at its lower end with a presser member 12. The tubular valve casing 11 has a 90 fixed arm 11^a extending rearwardly therefrom and to which is pivoted a valve operating member 25^a. Said member has an arm 26 and also has a bent arm 25 which engages the presser member 12 of the valve 95 rod. The arms 11^a, 26, enter the mouth of the user. A suitable resilient member 28 is arranged between the presser member 12 and the valve casing or tube 11 and is preferably arranged around the lower end of the 100 valve rod 13 and is here shown as a rubber sleeve. An adjusting screw 14 is mounted on the casing 11 and serves to limit the extent of movement of the valve member 9. The user by biting on the arms 11^a and 26 105 may move the former toward the latter and thereby partly turn the member 25^a on its pivot and in so doing cause the arm 25 to move the rod 13 upwardly and thereby raise the valve member 9 from its seat, and hence 110 cause compressed air to pass from the reservoir 21 to the air chamber 5.

In the form of the invention shown in Fig. 3 the presser member 12 of the valve 9 is operated by a connecting rod 17. An inflatable nipple 27, of rubber or other suitable material, is provided to operate the connecting rod and is here shown as held in an open-ended cylinder 15^a on a bracket 15^b which is attached to one side of the casing 1. The expansible nipple 27 is connected to one 10 end of a flexible tube 16 which has a bulb 27' at the other end. The said bulb is taken in the mouth of the user and when he bites thereon compressed air causes the expansible nipple to expand and thereby actuate the connecting rod and cause said connecting rod to open the valve, as will be understood and thus supply compressed air to the mask or casing 1 on the face of the user.

In the form of the invention shown in 20 Fig. 2, the air inlet valve 9 is arranged at one side of the casing 1 and the presser member 12 is manually operable.

In carrying the invention into practice, a bag or tank 21 of any suitable size and form 25 adapted to be carried upon the operator's back is filled with air sufficiently compressed so that the same may be utilized to serve as a main reservoir for drawing therefrom the air into the secondary reservoir 23 likewise carried by the operator around the 30 waist in addition to the one carried by him on his back, from which latter reservoir the air flows into the chamber 5 through the pipe 10, a suitable reducing valve operable 35 through a hand operating handle being provided for the purpose as shown at 24, Fig. 4.

Thus it will be seen that by providing the secondary reservoir 23 and thereby varying the pressure within the main reservoir 21 to 40 suit the surrounding pressure the operator is enabled to go to a greater depth of water, than would be possible without said secondary reservoir.

In the form of the invention shown in

Fig. 1, the pipe 18 which leads from the 45 valve casing 11 to the casing 1 has an elbow 19^a which is adjustably connected to said casing 1, the opposite end of said pipe 18 being connected by a union 19^b to a tubular arm 11^b which projects from one side of said 50 casing 11. This construction enables the valve mechanism to be bodily adjusted as may be required by the size or contour of the face of the user.

What I claim is:—

1. A respirator of the class described, comprising a mask to fit on the face of the user, compressed air supplying means, a connection including a valve between said mask and said compressed air supply means, 60 and mouth operated actuating means for said valve.

2. A respirator of the class described, comprising a mask to fit on the face of the user, compressed air supply means, a connection including a valve between said mask and said compressed air supply means, and mouth operated actuating means for said valve and comprising a relatively fixed arm and a relatively movable arm to enter the 70 mouth of the user.

3. In a respirator of the class described, a mask to fit on the face of the user, a compressed air supply means, a valve casing arranged exteriorly of said mask and connected to said mask and to said compressed air supply means, a controlling valve in said valve casing, mouth operated means to actuate said controlling valve, said valve casing and said valve actuating means being adjustable with respect to the mask.

In testimony whereof I affix my signature in presence of two witnesses.

RIICHI WATANABE.
